INVENTOR:

August H. Opperman,
BY

E. D. Silvius.
ATTORNEY.

UNITED STATES PATENT OFFICE.

AUGUST H. OPPERMANN, OF INDIANAPOLIS, INDIANA.

ELECTRICAL CURLING-IRON HEATER.

Application filed August 31, 1921. Serial No. 497,333.

To all whom it may concern:

Be it known that I, AUGUST H. OPPERMANN, a citizen of Germany, residing at Indianapolis, in the county of Marion and State of Indiana, have invented a new and useful Electrical Curling-Iron Heater, of which the following is a specification, reference being had to the accompanying drawings and to the letters and figures of reference marked thereon.

This invention relates to an electrically heated hollow device in which curling irons or other articles may be moderately heated, the invention having reference more particularly to a curling iron heater that is designed to be placed and used where most convenient in hair-dresser's apartments or elsewhere.

An object of the invention is to provide a heater which shall be so constructed as to be convenient for use for various purposes when moderate heating is desired, and which shall be compact and adapted to be conveniently repaired.

Another object is to provide an electrical heater which shall be so constructed as to be adapted for receiving and heating curling irons or other articles, and which shall be adapted also to radiate heat to articles on the exterior thereof.

A further object is to provide an electrical heater which shall be so constructed as to permit it to be used conveniently and safely by invalids or others to apply heat to portions of the body, and be suitable for drying small articles or pieces of fabric.

With the above-mentioned and other objects in view, the invention consists in a portable electrical oven adapted to apply heat both internally and externally, and having novel features of construction permitting ready renewal of the necessary heating element and connections thereof; and, the invention consists also further in the novel parts and combinations and arrangements of parts as hereinafter particularly described and further defined in the accompanying claims.

Referring to the drawings,—Figure 1 is a perspective view of the improved heater as preferably constructed and supplied with an electrical circuit connector; Fig. 2 is a horizontal central sectional and fragmentary plan of the heater structure; Fig. 3 is a fragmentary plan showing a portion of the heating element and its electrical connec-

tions, and illustrating structural improvements permitting the electrical connections to be easily made; Fig. 4 is an end view of the heater structure partially broken away; and, Fig. 5 is a fragmentary vertical central section, as on the line V—V in Fig. 4.

Similar reference characters in the different figures of the drawings indicate corresponding or like parts or features of construction herein referred to in detail.

The improved heater comprises a substantial foundation slab 1 which preferably is oblong in plan and non-metallic or a poor conductor of heat to guard against injury to fine furniture upon which it may be placed, and preferably the slab is provided with short legs 2 provided with bottom pads 3 permitting the legs to be placed upon furniture without scratching the surface thereof. Preferably the foundation slab has a top plate 4 thereon which may be metallic to impart mild heat to small articles which might be placed thereon. The oven portion of the heater comprises a head 5 having a leg 6 arranged upon the top plate 4 adjacent to one of the shorter ends thereof, and a head 7 having an aperture 8 thereon and having also a leg 9 arranged upon the plate 4 adjacent to the opposite shorter end thereof, the legs having screw threaded sockets 10 in their bottoms receiving bolts 11 inserted through the plate 4, the bolts having each a head 12 received into a recess 13 in the under side of the plate. The top plate 4 is secured to the slab 1 preferably by means of screws 14. A casing 15 is provided which conforms internally to the contour of the heads 5 and 7, preferably being approximately oval and the end portions of the casing receives the heads respectively, the lower portions of the ends of the casing having notches 16 and 17 receiving the upper portions of the legs 6 and 9 respectively. The upper portions of the casing are detachably secured to the upper portions of the heads by means of screws 18 and 19 respectively, each head having a screw threaded socket 20 in its top receiving the screw. The oven has a hollow core 21 therein that is shorter than the casing and correspondingly is approximately oval in cross-section, and one end of the core is removably inserted in the aperture 8 in the head 7. The casing 15 may be composed of aluminum when it is desired that it radiate heat, but it may in some cases be

composed of other material which may not be a conductor of heat. The core 21 may be composed of brass tubing or other suitable material, and the opposite or inner 5 end of the core has a head which preferably is composed of two plates 22 and 23 formed integrally with the wall of the core and bent inwards after slitting the wall so that the parts shall meet; and the end of the 10 core has also two pivot ears 24 and 25 extending integrally from the ends of the core wall. The head 5 has an arm 26 rigid on the central portion of the inner side thereof that is received between the ears and connected thereto by means of a pivot 27 to 15 permit relative movement of the head and the core when disconnected from the casing. The core 21 has a cover 28 thereon which is composed of suitable substance so 20 as to be a non-conductor of electricity, and a heating coil 29 is arranged on the cover and insulated thereby from the core, the coil having terminal wires 30 and 31 having suitable insulating covers as may be required. The head 5 is provided with two 25 contact pins 32 and 33 which have threaded shanks 34 and 35 respectively that are suitably secured to the head and insulated therefrom, and the shanks are provided 30 with binding nuts 36 and 37 respectively by which the terminals of the coil are secured to the inner portions of the shanks of the pins.

The conventional connector head 38 is connected 35 with the contact pins and has a circuit wire cord 39 connected therewith, which is provided with a suitable plug 40 for having connection with an electrical socket for obtaining electrical current for the heater.

The heater is usually of small proportions, and when connecting the terminals of the 40 heating coil to the contact pins the head 5 is turned pivotally as indicated in Figure 3 to afford ample space between one of the 45 shanks and the head of the core in which to manipulate the binding nut and easily connect the terminal to the shank, after which the head 5 is swung over in the opposite direction to permit the remaining terminal to be likewise easily connected to the 50 remaining contact pin. This arrangement permits the user of the heater, who may not be an expert or may not be provided with special tools, to easily substitute a new heating element for one which may have been 55 burned out, in many cases avoiding considerable expense incidental to the employment of an electrician.

In practical use the heater may be safely 60 placed upon polished furniture without resulting in damage thereto, atmospheric air being permitted to circulate under the foundation 1, and the foundation being of ample extent is not liable to be accidentally turned 65 over when hastily removing articles from

the heating oven in which curling irons or other articles may be properly heated conveniently. Various articles or substances may be placed upon the top of the casing 70 to be slightly heated or warmed, and small articles may be slightly warmed upon the top plate 4. The heater may be safely placed upon a bed and used as a foot warmer or may be so used when placed upon a floor. Also the casing of the oven may be placed in 75 contact with portions of the body to apply heat in case of illness or when for various reasons a person may desire it.

Having thus described the invention, what is claimed as new is:

1. An electrical heater including a casing having a head provided on its inner side with an arm having a pivot, the head being removably secured to the casing, two contact pins connected to the head adjacent to the 80 arm, a hollow core having an ear connected to the pivot, and a heating coil on the core and connected with the contact pins.

2. An electrical heater including a casing having two heads, one of the heads having an opening therein, the opposite one of the heads having an arm on the inner side thereof and also two contact pins adjacent to the arm, a hollow core having a head in one end thereof and also two pivot ears extending beyond the head, the ears having pivotal connection with the arm on the casing head, the opposite end of the core extending into the opening in the casing head, and a heating coil on the outer side of the core and having connection with the contact pins.

3. In an electrical heater, the combination with a hollow core, a casing, a head connected to the casing and having an opening therein receiving one end of the core, said end of the core being open, of a second head detachably secured to the casing and having pivotal connection with the opposite end of the core, two contact pins supported in said second head, and a heating coil on said core in connection with said pins.

4. In an electrical heater, the combination of a hollow core having a head in one end thereof and two pivot ears extending beyond the head, the head being composed of two parts extending integrally from opposite portions of the wall of the core, the opposite end of the core being open, a casing head having an arm on the inner side thereof and pivotally connected with said ears, two contact pins supported in said head, and a heating coil on said core in connection with said pins, with a casing detachably connected to said head, and a head connected to the casing and having an opening therein receiving the open end of the core.

5. In an electrical heater, the combination of a base plate having recesses in the under side thereof, two heads having each a leg arranged on said plate, each leg having a

threaded socket in its bottom, two screws extending from said recesses respectively and into said sockets respectively, the screws having heads arranged in the recesses, a casing connected to said heads, two contact pins supported in one of said heads, a hollow core supported at one end thereof by the head between the contact pins, the opposite end of the core being open and extending through the opposite one of said heads, and a heating coil on the core in connection with the contact pins.

6. In an electrical heater, the combination of a base plate, two heads having each a leg secured upon said plate, one of the heads having an opening therein, the opposite one of the heads having a pivot arm thereon and

also two contact pins extending through the head, the top of each head having a threaded socket therein, a casing embracing said heads and having two notches receiving portions of said legs respectively, two screws extending through the upper portion of the casing wall and into said sockets, a hollow core having one open end extending into said opening and having also two ears pivoted to said arm, and a heating coil on the core in connection with the contact pins.

In testimony whereof, I affix my signature in presence of two witnesses.

AUGUST H. OPPERMANN.
